United States Patent

Des. 235,777
Patented July 8, 1975

235,777

TANK FOR FAN FOLD TAPE

Gene D. Vedder, Granada Hills, Calif., assignor to
Ex-Cell-O Corporation, Detroit, Mich.

Original design application Nov. 6, 1972, Ser. No.
304,236, now Patent No. 230,362. Divided and this
application July 27, 1973, Ser. No. 383,333

Term of patent 14 years

Int. Cl. D14—02

U.S. Cl. D26—5 R

FIG. 1

FIG. 2

FIG. 3

FIG. 4

FIG. 1 is a perspective view of a tank for fan fold tape showing my new design;

FIG. 2 is a front elevational view thereof;

FIG. 3 is a top plan view thereof; and

FIG. 4 is a bottom plan view thereof.

This is a division of design application Ser. No. 304,236, filed Nov. 6, 1972, now Design Pat. No. D. 230,362, issued Feb. 12, 1974.

I claim:

The ornamental design for a tank for fan fold tape, as shown.
